UNITED STATES PATENT OFFICE.

ARTHUR W. BROWNE, OF ITHACA, NEW YORK.

PLAYING-CARDS.

1,140,441.

Specification of Letters Patent.

Patented May 25, 1915.

Application filed March 31, 1914. Serial No. 828,464.

To all whom it may concern:

Be it known that I, ARTHUR W. BROWNE, a citizen of the United States of America, and a resident of Ithaca, county of Tompkins, State of New York, have invented certain new and useful Improvements in Playing-Cards, of which the following is a specification.

This invention relates to playing cards for 10 a game of chemistry, or kindred science.

More particularly, my invention is a game 15 of chemistry, which is played by the use of cards bearing indications of the names of chemical elements, and their respective chemical symbols, and preferably also the 20 respective valence or valences of the chemical elements and a list of chemical compounds formed by the atoms of the chemical elements in accordance with the valence 25 of the same. If desired, the cards may also contain data of importance and interest with respect to the respective elemental substances or elements and the chemical compounds containing the same, or with respect 30 to chemical science or chemical industry in general, and the cards may also have thereon the pictures of chemists who are identified with researches in the discovery or commercial utilization of such elemental substance 35 or element or of a chemical compound thereof, or with other developments in chemical science or industry, or pictures of chemical apparatus, laboratories, or industrial works.

I have hereinafter set forth more specifically 40 one desirable form of game involving my invention, comprising cards each representing an atom of an elemental substance or element, each bearing the full name of the elemental substance, or the chemical element, 45 in a prominent portion of the card, and with the chemical symbol thereof proximate thereto, and the indication of the valence thereof, as by a Roman numeral, at another prominent portion of the card. Each of the

50 cards may also have printed thereon a list of chemical compounds containing one or more atoms of such elemental substance or chemical element in the valence indicated on such card. In those cases where an elemental substance or chemical element has two or 55 more valences, there are separate cards for the respective lists of chemical compounds, in each of which lists the chemical compounds comprise one or more atoms of the elemental substance or element in the valence indicated on the card. In other words, tak-

ing for example, iron which is bivalent and trivalent, there will be a card on which the valence two is indicated and a list of compounds containing iron in bivalent combination, and there will be another card for iron having the valence three indicated thereon and a list of chemical compounds containing iron in trivalent combination.

An object in playing a game with a deck 60 of cards comprising my invention is that each card represents one atom of an elemental substance or chemical element, and that a chemical compound enumerated in a list on a card is "formed" by taking as many 65 cards respectively bearing the names of the atoms of the elemental substances or chemical elements as is indicated by the formula of such chemical compound. For example, taking common salt or sodium chlorid, a 70 chemical compound of one atom of sodium (Na) and one atom of chlorin (Cl) such compound will be "formed" in playing the game by taking one sodium card and one chlorin card. Again, taking the chemical 75 compound ferric chlorid comprising one atom of iron (Fe) and three atoms of chlorin (Cl,) such compound will be "formed" in the play of the game by one card of iron and three cards of chlorin. The total number 80 of cards comprised in a deck will vary in accordance with the range of elemental substances or chemical elements and their respective chemical compounds desired to be included. Having chosen the elemental substances and chemical compounds or combinations 85 thereof, then there will be a minimum number of cards representing the atoms of the respective elemental substances or chemical elements which must be comprised in the deck.

Other features and objects of my invention will be more fully understood from the following description and the accompanying drawings, in which—

Figure 1 indicates a card representing an atom of the elemental substance or chemical element chlorin; Fig. 2 a card representing an atom of sodium; Fig. 3 a card representing an atom of hydrogen; Fig. 4 105 is a card representing an atom of bivalent iron; Fig. 5 a card representing an atom of oxygen; Fig. 6 a card representing an atom of trivalent nitrogen; Fig. 7 a card representing an atom of trivalent iron; Fig. 110 8 a card representing an atom of carbon; Fig. 9 representing an atom of quinque-

valent nitrogen and Fig. 10 a card representing an atom of sulfur.

As is indicated in the respective figures, the full name of the elemental substance or chemical element is printed at the upper left hand corner of each card; and the chemical symbol therefor is printed immediately below. Each card has printed thereon but one valence, the same being indicated by a 10 Roman numeral at the upper right hand corner of the card.

Figs. 1, 2 and 3 are cards representing respectively one atom of chlorin, sodium and hydrogen, which have each unity valence, so that each of these cards bears the indication I at the upper right. Fig. 4 is a card representing an atom of iron of the valence two, and accordingly has printed thereon at the upper right the indication II. 15 20 On the other hand, the card shown in Fig. 7 has printed thereon at the upper right the indication III for trivalent iron.

The card shown in Fig. 5 is a card representing an atom of oxygen which is bivalent, and accordingly the indication II is 25 printed at the upper right. The cards shown in Figs. 6 and 9 respectively are cards representing atoms of nitrogen of valences three and five, and accordingly the card in 30 Fig. 6 has the indication III and the card in Fig. 9 the indication V. The cards shown in Figs. 8 and 10 are cards representing an atom of carbon and an atom of sulfur respectively, the former being quadrivalent 35 and the latter sexivalent, so that the indications IV and VI are respectively printed at the upper right hand corners thereof.

The lists of chemical compounds on the 40 respective cards are subject to choice, and such lists may include any desired number of the chemical compounds containing an atom of the elemental substance or chemical element of the valence indicated thereon. Ordinarily, the list on a card embodies the 45 best known or most common compounds, but each list on the cards may be varied with respect to the number of chemical compounds or combinations of the atom represented by the card with other atoms, also 50 with respect to the number of compounds or combinations of the atom represented by the card with atoms of any one other elemental substance or chemical element.

I have found it desirable in general to 55 indicate the relative activity of the elemental substance or chemical element by the number of chemical compounds or combinations enumerated on the card representing an atom thereof. For example, the list 60 of chemical compounds on the nitrogen trivalent card, shown in Fig. 6, may contain but two compounds whereas the list of chemical compounds enumerated on the oxygen list, as is indicated in Fig. 5, may contain twenty-seven compounds, whereby even

the casual player without having any extended knowledge of the science of chemistry, derives the general impression that oxygen is far more active chemically than nitrogen. Accordingly, the relatively larger 70 number of compounds listed on the sodium card, see Fig. 2, indicates to the player that sodium is more active chemically than iron, either in bivalent or trivalent combinations, see Figs. 4 and 7. 75

For convenience, I have shown the lists on the various cards to be arranged alphabetically with respect to the atom of the elemental substance or chemical element other than that atom represented by the 80 card. Thus, on the chlorin card, see Fig. 1, the compounds calcium chlorid, chloroform, ferric chlorid, hydrochloric-acid, etc., are indicated in the order named since the respective chemical symbols of calcium, carbon 85 and hydrogen, etc., are alphabetically in the said order. It will be noted that the above described indications on the respective cards are arranged in double or duplex order whereby the printed matter on the left hand portion and at the top of each card reads properly irrespective of whether or not any card has been turned in the plane of its face. Accordingly, the cards are always ready to be gathered properly in the hand 90 of the player provided the cards are face up. If the list of chemical compounds containing an atom of any elemental substance or chemical element cannot be readily printed in a single column, then double columns, as 95 is indicated in Figs. 3 and 5, may be resorted to. It will, of course be understood that the double or duplex arrangement of the printed matter on the cards and the specific arrangement and enumeration of 100 the compounds or combinations in each list may be varied to secure the desired objects. 105

To indicate distinctions in chemical behavior of the atoms of the respective elemental substances or chemical elements, I 110 have arranged the respective cards to indicate whether the elemental substance or chemical element is electro-positive or electro-negative. One desirable form of indicating such behavior is by printing the cards of the electro-positive element in black, the cards of the electro-negative elements in red; of course, other colors may be employed, and other indices of such chemical behavior may be used. 115

The use of a deck of cards of the character described above may be illustrated by the following set of rules of play. Assume the deck to comprise thirty cards of chlorin "atoms", as shown in Fig. 1; four cards of sodium "atoms" as shown in Fig. 2; thirty cards of hydrogen "atoms" as shown in Fig. 3; two cards of iron "atoms" of the valence of two, and two cards of iron "atoms" of the valence of three, as shown 120 125 130

respectively in Figs. 4 and 7; thirty cards of oxygen "atoms" as shown in Fig. 5; two cards of trivalent nitrogen "atoms" as shown in Fig. 6; four cards of carbon "atoms" as shown in Fig. 8; two cards of quinquevalent nitrogen "atoms", as shown in Fig. 9; and two cards of sulfur "atoms" as shown in Fig. 10. To these cards may be added two calcium cards, two magnesium cards, 5 two zinc cards, two potassium cards, and two cards for sulfur of valency two, thus making a total number of chemical "atoms" of one hundred and twenty. After the deck has been shuffled, the dealer may deal say 10 five cards to each player to be held by the respective players without exposing such respective "hands" to one another. The dealer will also deal out other cards of the deck to the players in sets, say sets of ten 15 each, such sets to be placed on the table before the respective players face up, that is, only the top card of each pile will be exposed to all the players, or all the cards of such piles may be exposed.

20 The object of the game will be to form a "chemical combination" included in any list of chemical compounds or combinations on the cards by utilizing the proper cards or "atoms" and the proper number 25 of such "atoms". When such a "combination" is properly accomplished by a player by utilizing one or more cards from his "hand" with one or more cards from the exposed set of cards before him, such cards 30 or "atoms" when properly "combined" to form a chemical compound or combination are now placed in a heap or pile in the center of the table. The successful player is the one who first succeeds in using up all 35 the cards placed exposed on the table before him. Penalties may be provided for in case of failure of a player to use a card properly or for attempting to "combine" 40 improper cards or "atoms". The rules of 45 play may include the forming or building up of a second pile of cards or "atoms" on the table, wholly or partly exposed to the other players, with the privilege of utilizing any card or cards from such second pile 50 in conjunction with any card or cards from the first pile and any card or cards from the player's own hand. Such second pile may be formed whenever a player is unable to 55 make a "combination", by placing a card to form or build up such second pile. To simulate somewhat the conditions obtaining in chemical manufacture, more or less appropriate names may be applied to the 60 pile or piles of cards, as by calling each 65 "hand" a "drug room" or "stockroom"; the first pile or row of cards "raw material" or an "auxiliary stock room"; the second pile or row of cards a "waste product heap", the pile at the center of the table, the "finished product" or "formed mate-

rials", etc. The play of the game may be further extended by including points for successful "combinations" of the atoms based on the atomic or combining weights of the respective elements, in which case 70 each card may bear thereon the atomic weight of the element of which such card represents an "atom" thereof.

I have referred above to additional cards representing "atoms" of magnesium, zinc, 75 potassium, and calcium, and of sulfur of valence two. It will be understood that such cards will bear thereon the name of the chemical element, its symbol, the valence thereof, and a list of chemical compounds 80 containing one or more atoms of such chemical element, and properly colored or marked to indicate whether the element is electro-positive or electro-negative. As in the specific cards illustrated in the drawings, such 85 additional cards will include in their respective lists chemical compounds correlated to the other cards or "atoms", that is such compounds which are capable of being formed by the "atom" represented by the 90 card with one or more "atoms" of the remainder of the deck. Thus, a magnesium (Mg) card may include magnesium oxid (MgO), magnesium hydrate Mg(OH₂), magnesium sulfate (MgSO₄), etc.; a zinc 95 (Zn) card may list zinc chlorid (ZnCl₂), zinc oxid (ZnO), zinc sulfate (ZnSO₄), etc.; a potassium (K) card potassium chlorid (KCl), potassium carbonate (K₂CO₃), potassium bicarbonate (KHCO₃), potassium nitrate (KNO₃), potassium hydroxid (KOH), potassium sulfid (K₂S), potassium sulfate (K₂SO₄), etc. Of these cards, magnesium, 100 zinc and calcium are bivalent (II) and potassium is univalent. The sulfur (S) card 105 of the valence of two (II) may include in its list iron sulfid (FeS), sulfid of hydrogen (H₂S), potassium sulfid (K₂S), sodium sulfid (NaS), etc.

It will of course be understood that the 110 rules of play with cards arranged in accordance with my invention, may be varied, and that the specific indications as the cards hereinabove set forth may be modified without departing from my invention to attain 115 the desired objects.

What I claim and desire to protect by Letters Patent is:—

1. A deck of cards comprising a plurality 120 of cards each bearing a chemical notation corresponding to a certain chemical element and a list of chemical compounds containing said certain chemical element, and a plurality of cards each bearing a chemical notation corresponding to a certain other chemical 125 element and a list of chemical compounds containing said certain other element, at least one of said last-named chemical compounds containing said certain chemical element. 130

2. A deck of cards comprising a plurality of cards each corresponding to a certain chemical element and bearing a notation of its valence and a list of chemical compounds containing said certain chemical element in the said valence, and a plurality of cards each corresponding to a certain other chemical element and bearing a notation of its valence and a list of chemical compounds containing said certain other element in its said valence, at least one of said last-named chemical compounds containing also said certain chemical element in its said valence.
3. A deck of cards comprising a plurality of cards each bearing the chemical symbol corresponding to a certain chemical element, a notation of its valence and further a set of chemical compounds containing said certain chemical element in its said valence, and a plurality of cards each bearing the chemical symbol corresponding to a certain other chemical element, a notation of its valence and further a list of chemical com-

pounds containing said certain other element in its said valence, at least one of said last-named chemical compounds containing also said certain chemical element in its said valence.

4. A deck of cards comprising a plurality of sets of cards, said sets respectively corresponding to certain chemical elements, the cards of the respective sets bearing the chemical symbol and valence of the chemical element to which it corresponds and a list of chemical compounds containing such chemical element in its designated valence with the remaining of said certain chemical elements in their respective designated valences.

In testimony whereof I have signed this 40 specification in the presence of two subscribing witnesses.

ARTHUR W. BROWNE.
